US00D916536S

(12) **United States Design Patent** (10) **Patent No.:** **US D916,536 S**
Pedersen et al. (45) **Date of Patent:** **** Apr. 20, 2021**

(54) **DISPLAY FIXTURE**

- (71) Applicant: **TARGET BRANDS, INC.**, Minneapolis, MN (US)
- (72) Inventors: **Sara Lynne Pedersen**, Minneapolis, MN (US); **Grace Catherine Manuel**, Minneapolis, MN (US); **Scott E. Denby**, Minneapolis, MN (US); **Jeremy A. Clark**, Minneapolis, MN (US)

- (73) Assignee: **TARGET BRANDS, INC.**, Minneapolis, MN (US)

(**) Term: **15 Years**

(21) Appl. No.: **29/692,889**

(22) Filed: **May 29, 2019**

(51) LOC (13) Cl. **20-02**
(52) U.S. Cl. **USPC D6/672**

(57) **CLAIM**

The ornamental design for a display fixture, as shown and described.

DESCRIPTION

FIG. 1 is a top, front perspective view of a display fixture showing a first embodiment of our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

In the drawings, the broken lines depict unclaimed subject matter only. Bottom views are omitted as bottom surfaces of the display fixture are not claimed.

1 Claim, 6 Drawing Sheets
